UNITED STATES PATENT OFFICE.

ARTHUR R. SIEGLER, OF DENVER, COLORADO.

INTERNAL-COMBUSTION ENGINE.

Application filed July 7, 1924. Serial No. 724,584.

To all whom it may concern:

Be it known that I, ARTHUR R. SIEGLER, a citizen of the United States, residing at Denver, the city and county of Denver and 5 State of Colorado, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this 10 specification.

This invention relates to improvements in the construction of internal combustion engines of the type disclosed and claimed by me in my copending application Serial 20 No. 644,902, filed June 12, 1923.

In the type of engine to which this invention relates, the ordinary pistons which are connected to a crank shaft are eliminated and in their place columns of oil are 25 employed. On the surface of the oil, pistons, such as are described and claimed in my copending application, Serial No. 712, 622, filed May 12, 1924 are floated. The oil is acted upon by the force of the 30 explosion and forced into a compression tank, from which it flows to a turbine of the type shown and described in my copending application, Serial No. 714,670, filed May 20, 1924, after which it returns to the engine.

35 This invention relates more particularly to improvements in the construction of the engine employed for pumping the oil to the turbine.

40 My invention can be most clearly described and will be most readily understood when reference is had to the accompanying drawing in which the preferred embodiment thereof is illustrated, and in which:

45 Fig. 1 is a transverse vertical section through my improved engine, said section being taken on line 1—1, Fig. 2;

Fig. 2 is a longitudinal vertical section taken on line 2—2, Fig. 1; and

50 Fig. 3 is a vertical transverse section of a modified form of engine.

55 Numeral 1 indicates an engine block, which is secured by bolts 2 to a base 3. This engine block is provided with a plurality of cylinders 4, the sides of which have a number of ports 5 that open into an air

chamber 6. A sleeve 7 fits within the cylinder 4 and is provided with ports 8, which correspond to the ports 5. Sleeve 7 is adapted to be reciprocated within the cylinder to the extent required for closing and opening the passageway through ports 5 and 8 or about one-half of the distance between centers of ports 5. This reciprocation is accomplished by means of a crank shaft 9 60 that is rotated by means of an independent source of power, such as an electric motor (not shown). A connecting rod 10 extends from one of the crank pins 11 to a wrist pin 12 that extends from the bracket 13, 65 which, in turn, is secured to the sleeve 7 by means of a bolt 14. When the shaft 10 is rotated, the sleeve 7 will be reciprocated. A piston 15 is slidably related to the sleeve 7 and is reciprocated therein by means 70 which will hereinafter be described. Near the lower end of the cylinder are two ports 16 and 17 that communicate, respectively, with the chambers 18 and 19. A port 20 in the sleeve 7 serves to alternately open and close the ports 16 and 17. A pipe 21 connects chamber 19 with a pressure tank 22, from which a pipe 23 extends to the turbine 24. From the turbine a pipe 25 extends to a receiving tank 26 that is connected to the chamber 18 by means of a pipe 27. The parts are so arranged that the oil is under sufficient pressure in the receiving tank to raise the piston 15 to the top of the cylinder and to compress the 80 charge in the manner to be hereinafter described. The shaft 10 is also provided with a cam 28 for operating the poppet valves 29, which control the exhaust. The engine 85 cover or cap 30 is secured to the engine block by means of bolts 31. This cover has its under surface cut away so as to form a clearance space 32, which is so small that the air, when compressed, attains a temperature above that of the ignition point of the 90 fuel that is injected by the following means:

The check valve 33 is connected to a fuel supply (not shown) and communicates with the cylindrical chamber 34. A poppet valve 35 is seated in the lower end of the 105 chamber 34 and closes the same when seated, by the action of the spring 36. Secured to the stem 37 is a piston 38. When the valve 35 is open, fuel can flow from the supply to the clearance chamber 32 if the latter 110 does not contain air under pressure. A walking beam 39 is pivoted at 40 to the top

of a bracket 41. A rod 42 is pivotally connected to the outer end of the beam 39 whose inner end rests upon the upper end of the stem 37 in the manner shown in Fig. 1. The rod 42 extends downwardly through the guide lug 43 to such a distance that it will be struck by the end of the bolt 44, when the bracket 13, to which it is connected, approaches its upper limit of travel. This moves valve 35 downwardly and the piston 38 forces the fuel into the compressed air where it ignites and produces the pressure necessary for the working stroke.

Let us now consider a case in which the parts are in the position shown in Fig. 1 and let the shaft 10 be rotated. The first thing that will occur will be an upward movement of the sleeve 7, which causes the ports 5 and 8 to be moved out of alignment. After the ports above the piston has been closed, port 20 will come into alignment with the port 16 and oil will now flow from the tank 26 into the space underneath the piston and move the latter upwardly, thereby compressing the air in the cylinder chamber. As the air is compressed it heats, according to the well understood thermodynamic law of adiabatic compression. When the piston has reached the upper limit of its travel, the compression is complete. At this point fuel is introduced in the manner and by the means explained. The temperature of the air is above that of the ignition point for the fuel and the latter ignites. During this time the sleeve 7 has been moving upwardly and by the time the ignition of the fuel takes place, port 20 registers with port 17. As the piston is forced downwardly, the oil upon which it is supported flows outwardly into chamber 19 and from thence to the pressure tank 22. When the piston reaches the lower limit of its movement, the sleeve has moved downwardly sufficiently to open the ports leading to the air chamber 6. Just before this happens, however, the poppet valve 29 opens and permits the gases of combustion to escape. When the ports 5, 8 open, air from chamber 6 will rush into the cylinder and scavenge the same so that as the next cycle commences the cylinder will be charged with clean air. The port 45 is preferably connected to an air compressor so that chamber 6 always contains air under a moderate pressure. I may have as many cylinders as necessary, although I have shown only two. My engine, in reality, functions as a pump and delivers a steady stream of oil under pressure, which is then converted into power by means of a turbine or other liquid motor. By my present arrangement, a thorough cleansing of the cylinder is attained after every explosion and the compressed air is clean and fresh, thereby securing higher efficiency. The fact that the shaft 10 rotates

independently of the movement of the pistons 15 is believed to be a novel arrangement.

In Fig. 3 I have shown a slightly modified form of engine in which the poppet valves 29 are dispensed with and in which means is provided for compressing the air in the cylinder to some extent before the upward movement of the piston commences. In this modification a number of exhaust ports 46 are provided just over the upper end of the sleeve 7. These ports are of such width that the sleeve covers and closes them when the ports 5, 8 are opened. An exhaust manifold 47 surrounds the cylinder and is connected by means of a cylindrical tubular projection 48 with the pipe 49, which is bifurcated at 50, one end 51 connecting with the open end 52 of the closed cylinder 53 and the other part 54 opening into the atmosphere. When, after an explosion in the cylinder, the ports 46 are opened, the exhaust gases will flow into the exhaust manifold and down through the pipe 49. When it arrives at the bifurcation 50 a portion will enter the cylinder 53 and increase the pressure therein. When the air from the manifold chamber 6 begins to flow outwardly through the exhaust pipe 49, the pressure in the cylinder 53 will be greater than the pressure from the air and will force the latter back, compressing the same to a considerable extent so that when the ports 5, 8 and ports 46 are closed, the air will be under higher initial pressure than it otherwise would have been. This enables a higher charge of air to be obtained, which, in turn, increases the efficiency of the engine. The pistons 15 are very light and float on the oil. Their function is to protect the surface of the oil from the intense heat of the combustion which causes excessive carbonization.

It will be noted that I have produced a simple liquid pump which is well adapted to force liquid into a compression tank under high pressure. This liquid can then be used for any purpose desired.

Having now described my invention, what I claim as new is:

1. An internal combustion engine comprising a cylinder having a plurality of circular spaced rows of ports, a chamber about said cylinder, said chamber being connected to a compressed air supply, a sleeve within said cylinder, said sleeve having ports corresponding to the ports of the cylinder, and means for reciprocating said sleeve so as to open and close said ports.

2. An internal combustion engine comprising a cylinder having a plurality of circular spaced rows of ports, a chamber about said cylinder, said chamber being connected to a compressed air supply, a sleeve within said cylinder, said sleeve having ports cor-

- responding to the ports of the cylinder, means for reciprocating said sleeve so as to open and close said ports, and a piston slidably mounted in said sleeve. 35
- 5 3. An internal combustion engine comprising a cylinder having a plurality of circular spaced rows of ports, a chamber about said cylinder, said chamber being connected to a compressed air supply, a sleeve within 10 said cylinder, said sleeve having ports corresponding to the ports of the cylinder, means for reciprocating said sleeve so as to open and close said ports, a piston slidably mounted in said sleeve, and means for reciprocating said piston. 15
4. An internal combustion engine comprising, in combination, a cylinder having a closed bottom and an open top, a plurality of rows of ports arranged in spaced circles 20 about said cylinder, a chamber surrounding said cylinder and in communication with said ports, said chamber being connected to a source of compressed air supply, an exhaust port, means for opening and closing 25 said port, a fuel injector, means for operating said injector, a cylindrical slide member within said cylinder, a piston within said slide, said slide having ports for communicating with the ports in the cylinder, means 30 for reciprocating said slide so as to open and close said ports, a source of liquid under compression, and means for connecting the space beneath the piston to said source of compressed liquid so as to force the piston to move upwardly for the purpose of compressing a charge. 35
5. An internal combustion, liquid piston engine comprising a cylinder having a plurality of spaced rows of ports, a sleeve slidably mounted within said cylinder, said 40 sleeve having ports corresponding to the ports in the cylinder, means for periodically moving said slide so as to bring said ports into and out of alignment, a chamber surrounding the cylinder, said chamber being connected to a source of air under pressure, a piston slidably mounted in said slide, a source of liquid under pressure, means for connecting said liquid source to the space 45 underneath the piston whereby the latter will be forced to move upwardly, a fuel injector adapted to force a predetermined amount of fuel into the cylinder after the piston has reached the upper end of its compression stroke, and means for rendering 50 said injector operative. 55
6. An internal combustion engine comprising a cylinder, a sleeve movably mounted therein, a piston movably mounted in said sleeve, said sleeve and cylinder having cooperating port openings, an air chamber surrounding the cylinder, an exhaust manifold, and means connected with the exhaust manifold for causing a reverse flow of gas 60 after the exhaust pressure has subsided. 65

In testimony whereof I affix my signature.

ARTHUR R. SIEGLER.
